Primary Examiner—Dominic Simone

(74) Attorney, Agent, or Firm—Fross Zelnick Lehrman & Zissu, P.C.; Lawrence E. Apolzon, Esq.

(57) CLAIM

The ornamental design for a shoe, as shown and described.

DESCRIPTION

The Sole FIGURE is a front perspective view of a shoe showing my new design.

The broken line showing of the sole, heel, buckle, ankle strap, and portions of the upper is for illustrative purposes only and forms no part of the claimed design.

1 Claim, 1 Drawing Sheet
